Primary Examiner — Darlington Ly(74) *Attorney, Agent, or Firm* — Ann Lee(57) **CLAIM**We claim the ornamental design for a *bottle cap*, as shown and described.**DESCRIPTION**FIG. 1 is a top perspective view of a *bottle cap*, showing our new design;

FIG. 2 is a top plan view thereof;

FIG. 3 is a bottom plan view thereof *with the container portion shown in phantom removed*;

FIG. 4 is a back side elevation view thereof;

FIG. 5 is a front side elevation view thereof;

FIG. 6 is a left side elevation view thereof; and,

FIG. 7 is a right side elevation view thereof.

The broken lines [in the drawing] depict environmental subject matter only and form] *showing the container portion of the bottle is provided for the purposes of illustrating environmental structure and forms* no part of the claimed design.**1 Claim, 2 Drawing Sheets****Matter enclosed in heavy brackets [ ] appears in the original patent but forms no part of this reissue; matter printed in italics indicates the additions made by reissue.**(Amended)
